UNITED STATES PATENT OFFICE

97,154

DESIGN FOR A BOOK END

Sigmund Lee Wolffs, Chicago, Ill.

Application May 27, 1935, Serial No. 57,033

Term of patent 7 years

To all whom it may concern:

It is known that I, Sigmund Lee Wolffs, a citizen of the United States, residing at Chicago, Cook County, Illinois, have invented a new, original, and ornamental Design for a Book End, of which the following is a specification, reference being had to the accompanying drawing, forming a part thereof.

The figure is a perspective view of the book end showing my new design.

The design shown in the drawing has a rear side view not shown, which is a plain, flat surface following in vertical outside edges the contour of the outside edges of the design as shown.

I claim:

The ornamental design for a book end as shown, and described.

SIGMUND LEE WOLFFS.
